UNITED STATES PATENT OFFICE.

GEORGE EDWIN AVERY, OF NEW HAVEN, CONNECTICUT.

DESIGN FOR A POCKET-BOOK.

40,518.

Specification for Design.

Patented Feb. 22, 1910.

Application filed October 27, 1909. Serial No. 524,999. Term of patent 7 years.

To all whom it may concern:

Be it known that I, GEORGE EDWIN AVERY, a citizen of the United States, residing at New Haven, in the county of New Haven and State of Connecticut, have invented a new, original, and ornamental Design for Pocket-Books, of which the following is a specification, reference being had to the accompanying drawing, forming part thereof.

The figure is a perspective view showing the design of the pocket-book.

I claim:—

The ornamental design for a pocketbook, as shown.

GEORGE EDWIN AVERY.

Witnesses:

ANDREW T. BIERKAN,
WILLIAM C. AVERY.
